CLAIM

The ornamental design for a tiered beverage pong game system, as shown and described.

DESCRIPTION

FIG. 1 is a perspective view of a tiered beverage pong game system;

FIG. 2 is a front view of the tiered beverage pong game system;

FIG. 3 is a rear view of the tiered beverage pong game system;

FIG. 4 is a left side view of the tiered beverage pong game system;

FIG. 5 is a right side view of the tiered beverage pong game system;

FIG. 6 is a top view of the tiered beverage pong game system;

FIG. 7 is a bottom view of the tiered beverage pong game system; and,

FIG. 8 is a perspective view of the tiered beverage pong game system according to a second embodiment.

The broken lines and unshaded portions contained within broken line in FIG. 7 depict an unclaimed area of the tiered beverage pong game system.

1 Claim, 6 Drawing Sheets
